SIMULATED CLOCK TEACHING AID OR SIMILAR ARTICLE

Ralph T. Klepsch, 307 Lansdown Ave.,
Carle Place, N.Y. 11514

Filed Mar. 18, 1975, Ser. No. 559,550

Term of patent 14 years

Int. Cl. D19—07

U.S. Cl. D19—64

FIG. 1 is an elevational view of one face of a simulated clock teaching aid or similar article showing my new design;

FIG. 2 is a side view thereof; and

FIG. 3 is a view of the other face thereof.

I claim:

The ornamental design for a simulated clock teaching aid or similar article, substantially as shown and described.
